UNITED STATES PATENT OFFICE.

EDUARD SCHÜRMANN, OF KOEIZSCHENBRODA, NEAR DRESDEN, GERMANY.

TOBACCO-DELIVERY APPARATUS FOR CIGARETTE-MACHINES.

1,073,937.

Specification of Letters Patent.

Patented Sept. 23, 1913.

Application filed April 3, 1912. Serial No. 688,149.

To all whom it may concern:

Be it known that I, EDUARD SCHÜRMANN, managing director, and resident of Albertstrasse 5, Koetzschenbroda, near Dresden, 5 Saxony, German Empire, have invented a new and useful Improvement in Tobacco-Delivery Apparatus for Cigarette-Machines, of which the following is a specification.

The present invention relates to an improvement in tobacco delivery-apparatus for cigarette-machines and the object is to separate during the delivery of the tobacco its long fibers from the fine short fibers and to separately supply both kinds of fibers from 10 the delivery-apparatus. By this separation of the tobacco the fine short fiber tobacco can be excluded from the manufacture of cigarettes or it may be delivered in such a manner that it is situated within the interior 15 part of the cigarette and surrounded by layers of long fiber tobacco, whereby the injuring or raveling out of the cigarette is 20 fully prevented.

In the drawing, Figure 1 is a diagrammatic sectional elevation of a machine embodying my present invention. Fig. 2 is 25 a plan of a device for reducing the width of a layer of tobacco. Fig. 3 is a plan of the modified device for reducing the width of 30 a layer of tobacco. Fig. 4 is a front elevation of the device shown in Fig. 3.

a is the receptacle for containing the tobacco and *b* a trough-shaped projecting part which may be opened by hand and is 35 drawn in by the pull of weights as the tobacco contained in the receptacle *a* is taken therefrom. The sand and other foreign matter in the tobacco fall onto the bottom of the trough-like projection *b* partly during 40 the filling of the receptacle, and partly during the movement of the said trough-like projection, and can be discharged by the passage *c*.

d is a delivery-roller situated near the 45 bottom of the receptacle *a* and intermittently rotated. The periphery of this delivery-roller *d* is provided with cards arranged to point in a direction opposite to that of its rotary movement. By this 50 inclined position of the cards a tearing or severing of the tobacco fibers is prevented. On the contrary, they are delivered in an unbroken condition to a working roller *e* arranged to rotate above and at one side 55 of the vertical axis of the delivery-roller *d*.

Besides this the cards allow the short fiber tobacco after being freed to fill the spaces between the cards from which it is scraped by a brush-roller *f* to an endless belt *g* arranged in front of the delivery-roller *d*. *g* is an equalizing roller constantly rotating together with and above the working roller *e* its cards slanting in a direction opposite to that of its rotary movement. The roller *e* is engaged by the hairs of the brush-roller *f* and *h* is another endless belt situated in front of the working-roller *e*.

The weight of the tobacco only rests on the delivery-roller *d* arranged near the bottom of the receptacle, and not on the working-roller *e*. This latter forms the front part of said receptacle and takes its supply of tobacco from the quantity of tobacco fed by the roller *d*. The superfluous tobacco is scraped off by the equalizing roller *i*, which may be rotated constantly or, if preferred, intermittently.

The relative speeds of rotation of the rollers *d*, *e* and *i*, are as follows: The roller *d* makes one, the roller *e* 2.2 and the 80 roller *i* 1.4 revolutions in one minute. As the diameters of said three rollers do not materially differ one from another, the speeds at the peripheries are in approximately the same ratios.

During the time the supply of tobacco in *a* is at a higher level than the upper limit of the roller *e*, the spaces between the cards of the latter are filled and the tobacco scraped from the equalizing roller *i* by a brush-roller *f* will fall back to the tobacco supply. In proportion as this supply is reduced, the tobacco scraped from the working-roller *e* by means of the roller *i* tends to fill up the spaces between the cards on the roller *e*. The fibrous tobacco taken from this roller by means of the brush-roller *f* is fed to the traveling endless belt *h* and from it to the cigarette forming channel *m* in the same manner as the fine or short fiber tobacco fed by the endless belt *g*. If, therefore, long fiber tobacco only is fed or delivered to the entire width of the endless traveling belt *h* and fine or short fiber tobacco only on a central part of the traveling 95 endless belt *g* of a width equal to that of the endless band *h*, the result will be that the lower layer on the support-strip running within the channel *m* will consist of long fiber tobacco, the middle layer of a mixture 100 of the vertical axis of the delivery-roller *d*.

of long and short fiber tobacco and the upper layer again of long fiber tobacco. To narrow the width of the short fiber tobacco layer situated on the endless belt *g*, blades 5 or boards *n* may be arranged on said band as shown in Fig. 2, or the edges of said band may be bent in an upward direction by lateral rollers *o* obliquely arranged as shown in Figs. 3 and 4, or the width of the spreading channel situated in front of the brush- 10 roller *f* may be reduced by lateral plates.

By arranging the cards on the delivery- 15 roller *d* to point in a backward direction, said roller may run with a speed sufficiently high even for cigarettes of the greatest thickness without injuring or damaging the tobacco and it will only be necessary to regulate the speed of the rotary movement of the working-roller according to the thickness 20 of the cigarettes to be manufactured.

In combination with the intermittent rotary movement of the delivery-roller the arrangement of its cards to point in a backward direction is intended to obviate the 25 formation of a tobacco-roll in the receptacle *a* or at least the twisting movement of the tobacco therein.

The long and short fiber tobacco separately fed may be supplied to the forming 30 channel by one single endless belt only. In this case, the traveling endless belt *h* is dispensed with and the long fiber tobacco separately fed from the working-roller *e* and the brush-roller *h* falls down onto the endless 35 belt *g*, whereas the short fiber tobacco is fed by the brush-roller *f* to the endless belt *g*. The short fiber tobacco layer is reduced in width by lateral blades or boards similar to those shown in Figs. 2 and 3 and 40 this modified device permits the short fiber tobacco only to fall down into the central part of the long fiber tobacco layer.

The lower endless belt *g* may be shortened or reduced in length in such a manner 45 that the short fiber tobacco delivered by it does not reach the forming channel *m*, but is freely removed before so that it will be possible to make use if desired of the long fiber tobacco only.

50 I claim as my invention:

1. In a tobacco delivery apparatus for cigarette-machines, in combination with a tobacco receiving receptacle, a central working-roller constantly rotating and provided 55 with cards slanting in the direction of its rotary movement, a delivery-roller arranged to intermittently rotate below the constantly rotating working-roller and provided with cards slanting in an opposite direction to its 60 rotary movement and means for taking off

and delivering the fibrous tobacco, substantially as and for the purpose specified.

2. In a tobacco delivery-apparatus for cigarette-machines in combination with a tobacco receiving receptacle, a central working-roller constantly rotating and provided with cards slanting in the direction of its rotary movement, a brush-roller taking the fibrous tobacco from said roller, a delivery roller arranged to intermittently rotate below the constantly rotating working roller and provided with cards slanting in an opposite direction to its rotary movement, a brush-roller taking the fibrous tobacco from said delivery roller, an equalizing roller 65 rotating together with and above the working-roller and scraping off the superfluous tobacco from the central working-roller and a brush-roller scraping off the tobacco from said equalizing-roller back to the tobacco supply, substantially as and for the purpose specified. 75

3. In a tobacco delivery-apparatus for cigarette-machines, in combination with a tobacco receiving receptacle, a central working-roller, a brush-roller taking the fibrous tobacco from it, an endless traveling band receiving the long fiber tobacco from said working-roller, a delivery-roller, a brush-roller taking the fibrous tobacco from it 85 and an endless traveling band receiving the short fiber tobacco from said delivery-roller, substantially as and for the purpose specified. 90

4. In a tobacco delivery-apparatus for cigarette-machines, in combination with a tobacco receiving receptacle, a central working-roller, constantly rotating and provided with cards slanting in the direction of its rotary movement, a brush-roller taking the long fiber tobacco from said working-roller, an endless traveling band receiving said tobacco from the working-roller, a delivery-roller arranged to intermittently rotate below the constantly rotating working roller 100 and provided with cards slanting in an opposite direction to its rotary movement, a brush-roller taking the short fiber tobacco from it, and an endless traveling band receiving said tobacco from the delivery-roller, substantially as and for the purpose specified. 105

In testimony, that I claim the foregoing as my invention, I have signed my name in presence of two witnesses, this 20th day of 115 March 1912.

EDUARD SCHÜRMANN.
